UNITED STATES PATENT OFFICE.

ARTHUR CLIFTON CAINES, OF SWANSEA, ENGLAND.

CONSTRUCTION OF SHIPS.

1,008,008.

Specification of Letters Patent.

Patented Nov. 7, 1911.

Application filed June 28, 1911. Serial No. 635,790.

To all whom it may concern:

Be it known that I, ARTHUR CLIFTON CAINES, a subject of the King of Great Britain, residing at Swansea, in the county of Glamorgan, South Wales, England, have invented certain new and useful Improvements in the Construction of Ships, and of which the following is a specification.

The object of this invention is to provide an improved construction of ship, the hull of which shall be so shaped, and also provided with such an arrangement of water-tight compartments, that the possibility of the ship capsizing is rendered extremely remote, lateral rolling of the vessel is in greater part prevented, and the vessel has greater buoyancy when encountering either a running or a head sea, while at the same time owing to the arrangement of the water-tight compartments, the vessel is prevented from sinking in case of damage; beyond this, the object is also to produce, by the construction hereafter described, a drier vessel, and one the shape of which will tend to return the waves striking its sides, upon themselves.

In the construction of ships as at present known, it has been proposed to provide air or float chambers extending outward above the water line and beyond the sides of the vessel, with the object of preventing the ship from sinking or capsizing. It has also been proposed in ships provided with a belt of such air chambers, to construct the said vessel with a flat bottom, and it has even been suggested that the bases of the belt of float chambers should extend below the water line or at any rate below the load water line. Now according to my invention I extend the frames and plating of the hull in an outward and upward curve considered from the vertical central longitudinal plane of the ship, such float chambers being formed in this curved upper part which presents a concave external surface, while the lower part of the hull is curved also outward with a return curve so as to increase the width or beam of the hull toward the bottom, producing a bulbous form which merges into a flat bottom. With such a construction the

exterior of the side of the vessel presents a 50 longitudinally extending concave surface, such being produced by the outwardly longitudinally extending curved surface of the float chambers in conjunction with the outwardly and longitudinally extending curved 55 surface of the lower part of the hull, which latter surface merges, as aforesaid, into the flat bottom with which the vessel is constructed.

The construction according to this invention will be better understood by aid of the drawings, in which—

Figure 1 is a side elevation, Fig. 2 a plan view, Fig. 3 a cross section on the line X Y of Fig. 2, and Figs. 4 and 5 are cross sections respectively on the lines X¹ Y¹ and X² Y² of Fig. 2.

It will be understood that the drawings are diagrammatic, and are intended to illustrate the curvature of the vessel's sides and the location of the air or float chambers, while as will be well understood by naval architects, the actual lines of the vessel will be designed as circumstances may require.

Considering more particularly Figs. 1, 2 75 and 3, it will be observed that the frames and plating of the hull (Fig. 3) extend toward the main deck in an outward and upward curve at 1, presenting a concave external surface, while the lower part of the 80 hull is curved also outward into a bulbous form at 2, and the bulbous formation of the lower part of the side of the vessel merges into a flat bottom 3.

The float chambers are, as aforesaid, 85 formed in the upper outwardly curved part as indicated at 4, and by inspection of the plan it will be seen that the vessel is divided by water-tight bulk-heads 5, and the air chambers 4 in the construction shown, are 90 also divided transversely in line with the said bulk-heads. Beyond this, the air chambers 4 may be constructed around the stern of the vessel and extend in tapering formation up to the bow.

With a formation of hull such as illustrated at Fig. 3, the vessel has a considerable amount of stability when immersed to

the line A, at which point, with vessels ordinarily constructed, stability would only commence, and at the load water line B the stability of such a vessel and its resistance to rolling are greatly increased as compared with vessels as ordinarily constructed; for instance supposing there is a tendency to roll in the direction of the arrow, Fig. 3, such a tendency will be resisted by the overhanging concave wall of the air chambers at about the arrow C and simultaneously will also be resisted by the longitudinal bulbous formation of the lower part of the hull upon the opposite side as indicated at the arrow 15 D, while in conjunction with these curved surfaces, the flat bottom of the vessel still further increases the resisting power of the hull to such motions.

When considering Figs. 1 and 3, it is to be further observed that waves advancing for instance in the direction of the arrow E (Fig. 3) will tend, on striking the longitudinal concave surface of the hull side, to be turned back upon themselves, while the 25 vessel is thereby given, by reason of this longitudinal concave external surface, greater buoyancy when encountering either a head sea or a running sea, that is whether the vessel when being propelled through the 30 water, is encountering waves upon one side of the bow, or whether the waves following the vessel strike one or other side near the stern.

The air or float chambers do not restrict 35 the cargo-carrying capacity or interior space of the vessel, particularly when it is considered that extra space is given by reason of the longitudinal bulbous formation of the lower part of the hull as at 2, and more over they also prevent any possibility of 40 the vessel capsizing or actually sinking. In this connection the air chambers should be proportioned so that the opposite air chambers on each side of one of the holds, that is 45 between two bulk-heads such as 5, Fig. 2, should, when taken in conjunction with the bow and stern air chambers, be sufficient to support the weight of that part of the structure and the contents included in such a 50 hold.

The diagrams at Figs. 4 and 5 merely show a possible variation in the outline of the vessel as it approaches the bow and stern, but as has been previously stated, such lines of 55 the vessel will be designed and varied according to particular circumstances which present themselves to the naval architect.

What I claim as my invention and desire to secure by Letters Patent is:—

60 1. A ship comprising in combination a hull having outwardly extending air-tight float chambers at the upper part thereof, the outer side surface of said outwardly extending float chambers presenting a concave 65 curvature on the exterior of said hull and

extending throughout the length thereof, and the lower part of said hull having a longitudinally-extending bulbous formation to form in conjunction with the concave curvature of the external side surface of said float chambers, a concave longitudinally-extending external surface at about the load water-line, substantially as set forth. 70

2. In a ship, the combination with a hull and outwardly extending air-tight float 75 chambers at the upper part thereof, the outer side wall of said longitudinally-extending float chambers presenting a concave curvature on the exterior of said hull and extending throughout the length thereof; of a longitudinally-extending bulbous formation 80 at the lower part of said hull to produce the concave longitudinally-extending external surface at about the load water line by the conjunction of said concave curvature of the exterior wall of said float chambers with the upper part of said outwardly extending bulbous formation, and a flat bottom to said hull into which flat bottom the lower part of said bulbous formation merges, substantially as 90 set forth. 85

3. In a ship, the combination with a hull and outwardly extending air-tight float 95 chambers at the upper part thereof, said float chambers extending from the bow on both sides and throughout the length of said hull and extending around the stern thereof, the outer side wall of said float chambers presenting a concave curvature on the exterior of said hull, and transverse partitions 100 to divide said float chambers into compartments; of a longitudinally-extending bulbous formation at the lower part of said hull to produce a concave longitudinally-extending surface at about the load water line by the conjunction of said concave curvature of the exterior wall of said float chambers with the upper part of said outwardly extending bulbous formation of said hull, and a flat 105 bottom to said hull into which flat bottom the lower part of said bulbous formation merges, substantially as set forth. 110

4. In a ship, the combination with a hull having the frames and plating at the upper part of said hull structure curved outwardly 115 throughout the length of said hull and extending to the bow and around the stern of the vessel to present a concave curvature on the exterior of said hull, said frames and plating being also curved outwardly at the lower part of said hull into a longitudinally-extending bulbous formation to produce a concave longitudinally-extending external surface at about the load water line, an inner partition extending from the bow and around the stern of said hull, the lower edge of said partition conjoining said concave longitudinally-extending surface at about the load water line, and an upper deck conjoining said outwardly extending upper part 120 125 130

of said hull, said longitudinally-extending partition conjoining said deck to form overhanging water-tight chambers in said upper outwardly extending part, and transverse partitions subdividing said air-tight chamber to form float chambers; of a flat bottom to said hull into which flat bottom the lower part of said longitudinally-extending bulb-

ous formation of said hull merges, substantially as set forth.

In witness whereof I have hereunto set my hand in the presence of two witnesses.

ARTHUR CLIFTON CAINES.
